UNITED STATES PATENT OFFICE.

CASPER J. APP, OF LYNCHBURG, VIRGINIA.

QUADRUPLEX TELEGRAPH SYSTEM.

No. 909,511.

Specification of Letters Patent. Patented Jan. 12, 1909.

Application filed September 23, 1907. Serial No. 394,182.

To all whom it may concern:

Be it known that I, CASPER J. APP, a citizen of the United States, residing at Lynchburg, in the county of Campbell and State of Virginia, have invented certain new and useful Improvements in Quadruplex Telegraph Systems; and I do hereby declare the following to be a full, clear, and exact description of the invention, such as will enable others skilled in the art to which it appertains to make and use the same.

This invention relates to improvements in telegraph systems, and the object in view is the reduction or substantial elimination of the sparking produced by changes in polarity or potential, and the shortening of the period of no current on line, and preventing loss in current by eliminating certain resistances.

With this and further objects in view, the invention comprises certain novel constructions, combinations and arrangements of parts as will be hereinafter fully described and claimed.

In the accompanying drawing:—Figure 1 is an outline view of a transmitter and a pole changer, and the associated elements constituting one set for one terminal of a line. Fig. 2 is a perspective view of the transmitter. Fig. 3 is a similar view of the pole changer. Fig. 4 is an outline view of a modified form of transmitter, indicating the adaptability of the invention for providing an increased number of steps in variation of potential.

Referring to the drawing by numerals, 1 indicates generically the transmitter and 2 the pole changer.

The transmitter 1 consists of the usual lever 3 mounted on any suitable pivots 4 intermediate its length and provided with any ordinary armature 5 positioned for being influenced by the electro magnet 6 of the local circuit 7 controlled by usual transmitting key 8. The outer end of the lever 3 actuates a laterally extending contact spring or tongue 9 projecting in one direction and a similar spring or tongue 10 projecting in the opposite direction, said springs being insulated from each other and from the lever. The outer end of the lever 9 is connected to a post 12 to which the lead 13 is connected, and the outer end of the lever 10 is connected to the post 14 with which the lead 15 is connected. Posts 12 and 14 are so related to springs 9 and 10 that the tension

on these springs can be controlled by a slight movement of said posts. Above the spring 9 is positioned a post 16, carrying a contact set screw 17, and connected with lead 18, 60 and below the screw 9 is a similar post 19, having a similar contact set screw 20, and connected with lead 21. Above the spring 10 is a post 22 provided with a contact set screw 23 and connected with lead 24 and below the said spring 10 is a post 25 provided with a contact set screw 26, and connected with lead 27. The lead 18 extends to the positive pole of a source of high potential electrical supply 28, which may be a dynamo 70 as indicated in the drawing or a battery as preferred, the negative pole of the dynamo or other source of electrical supply being grounded. The lead 21 extends to the positive pole of a low potential source of electrical supply 29, the negative pole of said electrical source of supply being grounded. The lead 27 extends to the negative pole of a low potential source of electrical supply 30 and the positive pole of said source of 80 electrical supply is grounded. The lead 24 extends to the negative pole of a high potential source of electrical supply 31, and the positive pole thereof is grounded, delivering in either position of the lever 3 a potential practically equal to that of the source of current supply. Interposed in each of the leads 18, 21, 24 and 27 is the usual incandescent lamp 38 for safety resistance purposes.

The pole-changer 2 consists of the usual lever 32 pivoted, as at 33, intermediate its length and provided with any ordinary armature 34 influenced by the usual electro magnet 35 controlled by the local circuit 36, 95 said local circuit being governed by the usual transmitting key 37. Insulated from each other and from the lever 32 are springs or tongues 39 and 40 which are actuated by the free end of the lever and extend laterally from the opposite sides thereof. The outer end of the spring 39 is connected with a post 41, which post is connected to lead 42, which lead is connected with a contact set screw 43 carried by a post 44 beneath 100 the spring 39. Beneath the spring 39 extends a post 45 which carries the contact set screw 46 extending upwardly toward the spring 39, said post 45 being connected with the lead 15. The outer end of the spring 105 40 is connected with a post 47 which in turn is connected with lead 48. A post 49 ex-

tends above the spring 40 and carries a contact set screw 50. Post 49 is connected with the lead 13. Posts 41 and 47 are so related to springs 39 and 40 that the tension of the 5 springs is controlled by a slight movement of said posts.

For convenience of reference in tracing the circuits hereinafter, I shall refer to the several contact set screws and their posts 10 connected to leads as contact points, and for the sake of clearness the contact points have been indicated by arrow heads in the outline showing in Fig. 1. When the lever 3 is at its at rest position, the springs 9 and 10 rest 15 respectively upon the contacts 20 and 26, and when the lever 32 is in the at rest position, the spring 40 rests on the contact 43, and the spring 39 rests on the contact 46, the contacts 43 and 46 being so positioned 20 relative to their respective springs that as the free end of the lever 32 is elevated, the spring 40 first leaves the contact 43 and afterwards the spring 39 leaves the contact 46, and immediately after the spring 39 has 25 left the contact 46, the spring 40 will make contact with the contact 50.

The lead 48 extends to the branch wires 51 and 52 which may connect with the ordinary neutral relay, eliminating resistances 30 in branches 51 and 52, but by preference a neutral relay 53 is provided of the three coil type wound differentially, two of the coils being connected respectively with branches 51 and 52, and the third winding in series with 35 condenser 54 and an adjustable resistance 55, arranged in lead 56 connected with line 57. Obviously a suitable fixed resistance and an adjustable condenser may be substituted for the adjustable resistance 55 and 40 condenser 54. The opposite end of the third winding communicates with the ground wire 59 by lead 58. The wire 59 is provided with the usual balancing resistance 60 and condenser 61. The use of the condenser 54 45 and resistance 55 eliminates the necessity for resistance in the branches 51 and 52. The main line windings of the relay 53 are connected by leads 62 and 63 with the differential polarized relay 64, the windings 50 connected with lead 62 being also connected by lead 65 with line 57, and the windings connected with lead 63 being also connected with the grounded wire 59. The neutral relay specified is patented, and therefore is employed merely as a preferred form of structure in combination with the present improved elements, and the condenser 54 and resistance 55 are employed in conjunction with this form of relay obviating the resist- 55 ances usually employed in the branches 51 and 52, the arrangement of the condenser 54 and resistance 55 serving to increase the current on the main line by eliminating resistances usually found in branches 51 and 52, thereby establishing a more stable rela-

tion between the main and artificial lines, and further serving to reduce the interference due to the period of no current on line owing to reversals of the distant pole changer. This particular arrangement of the 70 condenser 54 also reduces the condenser capacity required to approximately one-half that at present utilized, and for this purpose the resistance of the windings of the relays 75 53 and 64 diverting a sufficient current for 75 energizing the condenser 54.

It is obvious, of course, that I do not propose to limit myself in the present invention to the particular arrangement of relays or to the particular type disclosed, as the present 80 invention is susceptible of use with any ordinary form of relay, such as has been commonly employed in quadruplex telegraph systems. While the three winding relay is the preferred arrangement, the relay 85 with three windings is not absolutely essential, and to demonstrate this point I have indicated by the dotted lines 66 and 67 the connections which might be provided so as to entirely eliminate the third winding from 90 the relay 53.

It is of course obvious, that four keys will be employed, of which two are utilized solely for interrupting and controlling the receiving of messages, while the other two 95 keys are utilized for the transmission of messages, and the two transmitting keys being really the only active keys in the operation, only the transmitting keys have been illustrated.

In order to make more obvious to those skilled in the art, the operation of the present invention, the several circuits will be traced according to all possible relationship of the two transmitting keys.

Assume that both the keys 8 and 37 are closed, starting at the positive pole of the high potential source of electrical supply 28 through lead 18 to contact point 17, through spring 9, to lead 13, to contact point 50, to 110 spring 40, to lead 48, to branches 51 and 52, where the current divides passing to the main and artificial lines in the usual manner, the arrangement of the condenser 54 and resistance 55 being the only novel 115 features at this point. Now assuming that the key 37 is opened and the key 8 left closed, the dropping back of the lever 32 will result in reversing the current to line 120 without alteration in the potential, the circuit being as follows: Beginning at the negative pole of the high potential source of electrical supply, through lead 24, to contact 23, to spring 10, to lead 15, to contact 46, to spring 39, to lead 42, to contact 125 43, to spring 40, to lead 48, and branches 51 and 52 etc., as above described. Thus it is obvious that the manipulation of the pole changer 2 simply serves to reverse the 130 current while the same potential is main-

tained. Now assuming that the key 8 is opened and the key 37 closed, there will be a change in potential, the following circuit being established: Beginning at the positive 5 pole of the low potential source of electrical supply 29, through lead 21, to contact point 20, to spring 9, to lead 13, to contact point 30, to spring 40, to lead 48, and to branches 51 and 52 etc., as above set forth, thus putting low potential, positive current to line, 10 practically equal to potential of source of current supply. Now assuming that the key 37 is opened and the key 8 remains opened, the current to line will be reversed without 15 altering the potential, the following circuit being established: beginning at the negative pole of the low potential source of electrical supply 30 through lead 27, to contact point 26, to spring 10, to lead 15, to contact point 46, to spring 39, to lead 42, to contact point 43, to spring 40, to lead 48 and to branches 51 and 52 etc., as above set forth. Incoming 20 currents or impulses are adapted to traverse substantially a reverse direction to the outgoing impulses, but in order to more clearly indicate the travel of the same the various circuits will be traced. Assuming 25 that both keys 37 and 8 are closed, and starting with a current or impulse coming in over line 57, the same passes to wire 48, spring 40, contact point 50, wire 13, spring 9, contact 17, wire 18, through the positive lead of dynamo 28, and from thence to the ground. Now assuming that key 37 is open 30 and key 8 left closed, the dropping back of lever 32 will result in reversing the current to line without altering the potential, the path traversed by the in-coming impulses being over wire 48, spring 40, contact 43, 35 wire 42, spring 39, contact 46, wire 15, spring 10, contact 23, wire 24, the negative lead of dynamo 31, and from thence to the ground. Now assuming that key 8 is opened and key 37 closed, there will be a change of 40 potential, and the in-coming impulses will traverse wire 48, spring 40, contact 50, wire 13, spring 9, contact 20, wire 21, the positive lead of dynamo 29, and from thence to the earth. Assuming that key 37 is open, and 45 key 8 remaining open, the current from line will remain the same potential, but will be reversed, the path traversed being wire 48, spring 50, contact 43, wire 42, spring 39, contact 46, wire 15, spring 10, contact 26, 50 wire 27, the negative side of dynamo 30, and from thence to the ground. Thus it becomes obvious that manipulation of the transmitter 1 varies the potential to line and the manipulation of the pole changer 2 55 reverses current to line. During the reversing of the current to line there is a tendency of sparking which burns the points and reduces the efficiency of the apparatus. In the present improved structure this sparking is largely, and in fact almost entirely

eliminated by the series of three air gaps introduced during the period of reversals of the pole changer, thus permitting a closer adjustment of the reversing device and materially reducing the period of no current in the neutral relay at distant end, which of course, tends to prevent mutilation of signals received by that relay. 70

Obviously while the transmitter and pole changer have been indicated as positioned 75 horizontally, they may be positioned vertically, or otherwise as found preferable without departing in any degree from the spirit and scope of the present invention. The lever of either the pole changer or the transmitter may be disposed vertically with the electro magnet controlling the same disposed horizontally instead of the parts being arranged as shown, and various detail alterations may be made within the scope of the 80 present invention. 85

Several phases of the present invention which I consider of considerable importance reside in the elimination of the wasteful resistances ordinarily employed in dynamos or 90 other heavy current sources of supply for reducing the voltage when a change in potential is desired, as by the improvement in this respect, the transmitter will deliver a potential practically equal to the potential 95 of the source of current supply and insures delivery of a steadier current to line, variations in current having formerly resulted from changes in value of the resistances, heretofore used, due to overheating. The 100 elimination of the resistances of course effects a considerable economy in the cost of maintenance and operation.

Obviously, the present improved pole changer may be employed in conjunction 105 with a duplex telegraph system and also with all forms of multiplex systems employing a pole changer, and when so used it will be found that higher speed and better signals will result than heretofore on account of the 110 closer adjustment possible.

It will be observed that the levers of the pole changer and transmitter are used solely to actuate the tongues or springs resting on their free ends, which results in a good firm 115 contact being made in any position of these levers, and thus firmer signals are produced at greater speed and with more margin than is now possible.

I have indicated in Fig. 4 an outline of a 120 slight modification consisting in the employing in combination with the transmitter 1, in addition to the elements above described, which in Fig. 4 bear the same numerals as in the other figures and to which the foregoing description will accurately apply, two sets of contracts 68, 68 connected to a source of electrical supply representing an intermediate potential. For the purpose of readily disclosing this feature, ordinary batteries 125 130

have been indicated conventionally in Fig. 4, but obviously dynamos might be employed if preferred, and from the indication of the intermediate potential points 68, it becomes 5 obvious that as many steps of difference in potential may be utilized as desired, for increasing the number of variations in potential of the current to line, at a potential practically equal to that of the source of 10 current supply, the utility of which is of course well known to those skilled in the art.

What I claim is:—

1. In a telegraph system, the combination 15 of a plurality of sources of positive electricity of different potential, a plurality of sources of negative electricity of different potential, a transmitter for putting to line different currents of electricity according to their potential, a pole changer for putting 20 to line currents of electricity according to their nature, an artificial line and a main line branched from the lead from the pole changer, a neutral and a polarized relay interposed in said lines, a condenser disposed between one of said relays and the 25 main line and an adjustable resistance in series with said condenser.

2. In a telegraph system, the combination 30 of a plurality of sources of positive electricity of different potential, a plurality of sources of negative electricity of different potential, and a transmitter for putting to line different currents of electricity according to their potential, said transmitter comprising 35 a pivotal lever, an electro magnet for operating said lever, springs actuated by said lever and insulated therefrom and from each other, a contact for positive electricity spaced at one side of one of said springs, 40 and a similar contact for similar electricity of different potential spaced at the other side of said springs, a contact for negative electricity spaced from one side of the other of said springs, and a contact for similar 45 electricity of different potential at the other side of the last mentioned spring, the said spring being adapted to be moved by movement of the lever under the action of said magnet from a position in contact with one 50 set of contacts to a position in contact with the other set, delivering in either position a potential practically equal to the voltage of current supply and thereby increasing the current in line, and leads permanently connected with the respective springs.

3. In a telegraph system, the combination 55 of a plurality of sources of positive electricity of different potential, a plurality of sources of negative electricity of different potential, a transmitter for putting to line different currents of electricity according to their potential, and a pole changer for putting to line currents of electricity according to their polarity, said pole changer comprising 60 a pivotal lever, an electro magnet for 65

operating the same, a spring mounted on the side of said lever and rigidly held in place and having one end contacting with said lever, insulating places on said lever for insulating said spring, a contact for negative 70 electricity for one of said springs, a contact for positive electricity for the other of said springs, a lead extending from the first mentioned spring, a contact communicating with said lead and disposed for contacting with 75 the second mentioned spring when said spring is not in contact with said second contact for positive electricity, and a lead to line permanently engaging the second mentioned spring the positive and negative contacts being disposed for being alternately engaged according to the position of the said lever assumed under the action of the electro magnet.

4. In a telegraph system, the combination 80 of a plurality of sources of positive electricity of different potential, a plurality of sources of negative electricity of different potential, a transmitter for putting to line different lines of electricity according to 85 their potential, and a pole changer for putting to line currents of electricity according to their nature, said pole changer comprising 90 a pivotal mounted lever, an electro magnet for operating the same, means for 95 operating the magnet whenever desired, a spring positioned on each side of said lever and extending at right angles thereto, means for rigidly holding said springs in position, means for adjusting the tension of said 100 springs, insulation mounted on said lever and insulating said springs from each other, a contact for positive electricity placed at one side of said spring, and a similar contact for similar electricity of different potential placed at the other side of said 105 spring, a contact for negative electricity placed at one side of the other of said springs, and a contact for similar electricity of different potential placed at the other side of the last mentioned spring, the said 110 spring being adapted to be moved by said pivotally mounted lever under the action of said magnet from a position in contact with one set of contacts to a position in contact 115 with the other set for delivering in either position a potential equal to the voltage of current supplied.

5. In a system of telegraphy, the combination 120 with a plurality of high potential sources of electrical energy, and a plurality of low potential sources of electrical energy, a transmitter for putting to line different currents of electricity according to their potential, said transmitter comprising a plurality of binding posts, springs rigidly secured to said binding posts and extending towards each other, means for varying the position of said binding posts for regulating 125 the tension of said springs, contacts posi- 130

tioned above and below both of said springs, means for insulating said springs from each other, means for moving said springs out of contact with one set of said contacts and 5 into contact with the remaining contacts, leads from said contacts, a pole changer for putting to line currents of electricity according to their polarity, a relay a bifurcated lead from said relay to said pole 10 changer, a winding on said relay connected

at one side with the artificial line and at the other side to the main line, and a condenser interposed in said connections, and a resistance in series with said condenser.

In testimony whereof I affix my signature 15 in presence of two witnesses.
